US0D1070789S

(12) **United States Design Patent** (10) Patent No.: **US D1,070,789 S**
(45) Date of Patent: ** Apr. 15, 2025

(54) **OPERATING CONSOLE FOR MACHINE TOOL**

(71) Applicants: **DMG MORI CO., LTD.**, Nara (JP);
GILDEMEISTER Beteiligungen GmbH, Bielefeld (DE)

(72) Inventor: **Matus Prochaczka**, Lochau (AT)

(73) Assignees: **DMG MORI CO., LTD.**, Nara (JP);
GILDEMEISTER Beteiligungen GmbH, Japan
Bielefeld (DE)

(**) Term: **15 Years**

(21) Appl. No.: **29/819,074**

(22) Filed: **Dec. 13, 2021**

(30) **Foreign Application Priority Data**

Jun. 15, 2021 (JP) ..... 2021-012787 D
(51) **LOC (15) Cl.** **13-03**

(52) **U.S. Cl.**
USPC **D13/162**

(58) **Field of Classification Search**
USPC D14/315, 316, 317, 318, 320, 327, 342,

(57) **CLAIM**

The ornamental design for an operating console for machine tool, as shown and described.

DESCRIPTION

FIG. 1 is a front view of an operating console for machine tool in accordance with my new design;

FIG. 2 is a rear view thereof;

FIG. 3 is a right side view thereof;

FIG. 4 is a left side view thereof;

FIG. 5 is a top view thereof;

FIG. 6 is a bottom view thereof; and,

FIG. 7 is a perspective view thereof.

1 Claim, 6 Drawing Sheets
